Application June 22, 1939, Serial No. 280,530

12 Claims. (Cl. 315—271)

Our invention relates to electric discharge apparatus and has particular relation to electric discharge valves of the pool type which are ignited by the application of a potential to an insulated ignition electrode.

In Figs. 2, 3 and 4 of the French Patent No. 453,113, published May 31, 1913, electric discharge devices of the insulated-ignition-electrode type constructed in accordance with the teachings of the prior art of which we are aware are illustrated. In general, the ignition electrode in a prior art discharge device comprises a metallic conductor such as a wire, a rod, or a column of mercury disposed in a relatively thick glass jacket. The electrode is immersed in the cathode of the discharge device with the glass serving as an insulator between the conductor and the cathode. When a potential of steep wave front is applied between the wire and the cathode, a discharge is initiated in the device.

Although the prior art discharge valves of the insulated-ignition-electrode type in which the electrodes are used for the occasional starting of an arc have been known for many years, they have not been adopted for repeated periodic ignition at commercial frequencies. When used for repeated ignition, the prior art electrodes do not cause the arc to be ignited reliably every cycle, but miss occasionally, and the frequency of such missing increases with use so that in a short time the valves become inoperative. Higher voltage applied to the ignition electrode increases its reliability for repeated ignition, but even at the highest potentials to which the insulating material can be safely subjected, the operation is still faulty, and the life short. High potentials are, moreover, undesirable in an industrial plant because they are a source of danger to the employees and therefore require expensive protective apparatus. While the high potential requirement may be overlooked, in many cases the short life is fatal. Continuous power supply is indispensable to a modern industrial plant and a device which has a tendency to obstruct its flow will not be used regardless of what it may offer to counteract the deficiency.

It is accordingly an object of our invention to provide a discharge device of the insulated-ignition-electrode type wherein the ignition potential required for reliable repeated ignition shall be of relatively moderate magnitude.

Another object of our invention is to provide an electric discharge device of the insulated-ig-

nition-electrode type that shall be capable of continuous operation over an extended period.

5 A more specific object of our invention is to provide an ignition electrode for a discharge device of the insulated-ignition-electrode type that shall be capable of extensive use in repeated ignition without failing.

An ancillary object of our invention is to provide a novel circuit arrangement incorporating 10 valves of insulated-ignition-electrode type that is particularly adapted for resistance welding and like purposes.

15 More generally stated, it is an object of our invention to provide a discharge device of the insulated-ignition-electrode type that shall be capable of withstanding the wear and tear of everyday commercial use.

Our invention arises from the realization of the 20 causes of the deficiencies in the prior art discharge devices, and may be understood in the light of the theory advanced in United States Patent No. 2,069,283 to Joseph Slepian and Leon R. Ludwig, dated February 2, 1937, and assigned to Westinghouse Electric & Manufacturing Company, in which an ignition electrode of a high 25 resistance material is described. There, it is shown (Fig. 11) that the conduction current flowing through the igniter into the mercury takes a very high density at the junction of the igniter with the mercury, and that the high current density with the associated high local electric 30 gradient causes the ignition of the arc. Now, a varying voltage applied to an insulator will also cause currents known in the art as "displacement currents" to flow through the insulator. Displacement currents also concentrate at the junction of the cathode and the ignition electrode 35 making it possible that an arc may start there. The magnitude of the displacement currents will 40 depend directly on the magnitude of the electric gradient, and the rate at which it is changed, i. e., on the frequency of the gradient. Therefore, it is desirable that the frequency be high. Also, it is found that as long an interval as 100 microseconds is required for the arc which is formed 45 as a result of ignition to reach to the main anode of the tube. Hence, it is desirable for the high frequency current to the igniter be maintained for that length of time for each repeated 50 ignition. Ignition potential of large magnitude is required in the prior art arrangements because of the thickness of the insulator, since a definite gradient is needed for a given displacement current at a given frequency.

The ignition of the arc then is dependent on

the intensity of the displacement current which flows through the insulator when the varying ignition potential is impressed. We have found that in the more remote parts of the igniter, the current should be of the order of 1 ampere per cm.² to produce reliable ignition by its concentration at the mercury junction in the usual case where the anode-cathode potential is of the order of 100 volts. The displacement current for a given voltage is dependent on the thickness of the insulator between the conductor and the cathode. The greater the thickness of the insulator the smaller the displacement current produced for a predetermined potential. Because the insulators in the prior art apparatus are relatively thick, the potential required is relatively high. As one aspect of our invention, we accordingly contemplate the use of an insulator of small thickness. We have found that under proper circumstances, an insulator having a thickness of only .003 inch operates satisfactorily.

Further analysis of the operation of the prior art discharge valves reveals that the briefness of the service which they afford may, at least in part, also be attributed to the use of insulators having a substantial thickness. To properly initiate a discharge it is desirable that the potential impressed between the ignition conductor and the cathode persist for a substantial time interval which is of the order of 100 micro-seconds in length. To properly apply the ignition potential for such an interval, it is desirable that an alternating potential of a frequency which may vary from several hundred cycles to several hundred-thousand cycles per second be impressed. The application of an alternating potential sufficient to produce a displacement current of one ampere per cm.² to an insulator results in the development of substantial energy losses in the insulator. Where the insulator is composed of relatively thick material, a substantial temperature elevation within the material arises therein when the ignition potential is repeatedly applied. Since the material used in accordance with the teachings of the prior art is glass, in which the dielectric losses increase with temperature, a thermal instability may arise. This leads to dielectric failure. The elevated temperature also induces crystallization in the glass with cracking and consequent failure.

Where the insulator is relatively thin as contemplated in accordance with our invention, it assumes the same temperature throughout and the difficulty is to a certain extent suppressed. While thin glass insulators are satisfactory, difficulty is involved in coating a conductor with a thin layer of this material. This difficulty may be avoided in accordance with a further aspect of our invention, by replacing the glass with a more suitable insulating material. Mica may be used but we prefer a ceramic substance such as vitreous enamel or porcelain. Not only do ceramic insulators facilitate the construction of a suitable ignition electrode but they are particularly propitious for use in an ignition electrode because of their mechanical properties.

In accordance with a further aspect of our invention, discharge devices of the insulated-ignition-electrode type are used to control the supply of power to an alternating-current load, such as a resistance welder. A pair of discharge valves are, in such a case, connected in antiparallel between the load and the source and when one of the valves is conductive, the potential across the

other valve is relatively small and insufficient for ignition. The ignition potential may here conveniently be applied continuously to both valves since the possibility of backfire during the reverse cycle, which usually arises by reason of the continuous supply of ignition potential is precluded by the small potential across the non-conductive valve.

The novel features that we consider characteristic of our invention are set forth with particularity in the appended claims. The invention itself, however, both as to its organization and its method of operation, together with additional objects and advantages thereof, will best be understood from the following description of a specific embodiment when read in connection with the accompanying drawing in which:

Figure 1 is a diagrammatic view showing a preferred embodiment of our invention; and

Fig. 2 is an enlarged view of a portion of a discharge device showing an essential feature of our invention.

Our invention is shown specifically as applied to a welding arrangement although it has general applicability. The apparatus shown in the drawing comprises a welding transformer 1 across the secondary 3 of which a pair of welding electrodes 5 are connected. The electrodes 5 engage the material 7 to be welded and when the transformer 1 is energized, welding current flows through the material. The primary 9 of the transformer 1 is supplied from the line conductors 11 and 13 of an alternating-current source (not shown) of the usual commercial 60 cycle type through a pair of anti-parallel connected discharge valves 15 and 17 of the insulated-ignition-electrode type.

Each of the discharge devices 15 and 17 is made up of a pair of coaxial metallic cylinders 19 and 21. The inner cylinder 19 is shorter than the outer one 21 but is symmetrically disposed relative thereto and the ends of the cylinders are joined by strips 23 of suitable construction to form an annular space through which a cooling liquid such as water may flow. The inner cylinder 19 is composed of stainless steel and a stainless steel ring 25 is sealed, preferably by welding, near its upper end. From the inner surface of the ring 25, a cylinder 27, composed of a cobalt-iron-nickel alloy, known in the art as Kovar alloy, extends upwardly. The alloy cylinder 25 is welded to the ring in such manner that the joint is gas-tight. A cylinder 29 of glass having the proper thermal properties is sealed to the upper rim of the alloy cylinder 27 and a cobalt-nickel-iron alloy cap 31 is sealed to the upper rim of the glass. A conducting rod 33 forming a gas-tight joint with the cap 31 projects through the cap to a point well below the ring 25 and carries at its lower end a block 35 composed of carbon or a metal which functions as anode for the device. The glass cylinder 29 insulates the anode 35 from the wall 19.

Near the lower end of the inner wall 19, a disc 37 of a metal such as stainless steel, is welded. The disc is provided with a plurality of cobalt-nickel-iron-alloy eyelets 39 and 41. Through one of the eyelets 39, a tube 43 of glass of the type that seals to the alloy, extends. The tube is used for exhausting the valve, and after the device has been exhausted, it is sealed off. Through the other eyelet 41, another glass tube 45 is sealed. The latter extends well up into the interior of the cylinder 19 and a cobalt-nickel-iron alloy wire 47 is sealed through it. The wire

41 is bent at right angles at two points to form a hairpin like structure with the free end extending towards the disc 37. The free end of the wire 47 is covered with a thin layer 49 of insulating material. The insulator 49 may be glass, but is preferably a ceramic substance such as vitreous enamel, porcelain, or the like. The thickness of the insulator is preferably of the order of .003 inch. However, we have found that glass having a thickness of the order of .020 inch may also be used with a certain degree of success.

While the conductor within the insulator 49 is in the embodiment specifically shown composed of the cobalt-nickel-iron alloy, it may be composed of other conductive materials. For example, a steel or copper wire may be welded to the wire sealed through the sleeve 45 and bent into the hairpin shape and covered with an insulator at its free end. Alternatively, a short cylindrical bar covered with the insulator may be suspended from the free end of the wire sealed through the sleeve.

The mercury 51 which in the preferred practice of our invention constitutes the cathode of the discharge device is disposed on the disc 37 to such a height that it covers the lower portion of the insulating layer 49 and extends above the lower tip of the wire 47. The height of the mercury 51 may be regulated by the exhaust tube 43 before the latter is sealed off.

On occasions we have found that ignition is facilitated by the presence of a gaseous atmosphere at a pressure of several microns in the device. The desired gaseous medium may be obtained either by heating the mercury or by introducing a noble gas before the tube 43 is sealed off.

The ignition potential required for rendering the valves 15 and 17 conductive is of the order of 150 volts and is supplied from an oscillation generator 53. The latter comprises a high-vacuum thermionic tube 55 of capacity sufficient to transmit the necessary potential. The anode 57 and the cathode 59 of the tube are interconnected through a primary winding 61 of a transformer 63 and the adjustable taps 65 and 67 of a voltage divider 69. The divider 69 is supplied from the line conductors 11 and 13 through a suitable rectifier 71. Across the primary 61 a variable capacitor 72 is connected. The capacitor may be set so that the frequency of the potential supplied by the oscillator 53 is of the desired value. The transformer 63 is provided with a pair of secondary windings 73 and 74. The windings 73 and 74 are each connected between the conductor 47 and the cathode 51 of a corresponding valve 15 and 17, respectively.

The primary 61 is coupled to a coil 75 which is connected between the grid 77 and the cathode 59 of the tube 55. When current is not to be supplied to the load 7, the grid circuit for the tube 55 extends from the grid 77 through the coil 75, engages movable and fixed contacts 79 and 81, respectively, of a timing relay 83, the closed movable contact 85 of a circuit controller 87, which may be a push button or a foot switch, another movable tap 89 of the voltage divider 69, the central tap 67 of the divider to the cathode 59. The voltage divider 69 in the circuit just traced supplies a biasing potential to the tube 55 which is of such magnitude that the current flow through the tube is zero and the oscillator is therefore deenergized.

To initiate a welding operation, the circuit controller 87 is operated and the grid circuit through

the biasing potential provided by the voltage divider 69 is interrupted when the closed contact 85 is opened. Another contact 91 of the controller 87 is, however, closed and the grid 77 of the tube 55 is connected to the cathode 59 directly through the coil 75 in a circuit which extends from the grid 77 through the coil 75, the closed contacts 79 and 81 of the timing relay 83, the closed contact 85 of the controller 87 to the cathode 59. The tube 55 in the oscillator circuit 53 is now rendered conductive and alternating potential of a frequency determined by the setting of the capacitor 72 is impressed between the ignition electrodes 47-49 and the cathodes 51 of the discharge devices 15 and 17.

At the instant when the circuit controller 87 is operated and the ignition potential is first supplied, the anode-cathode potential impressed on one of the devices 15 or 17 is positive while that impressed on the other is negative. For the purpose of explaining the operation, we may assume that initially the left-hand discharge device 15 is supplied with positive anode-cathode potential. Initially, therefore, the left-hand device 15 is rendered conductive and current flows from the upper line conductor 11 through the anode 35 and cathode 51 of the device, the primary 9 of the welding transformer 1, to the lower line conductor 13. The flow of current through the primary of the welding transformer induces corresponding current flow in the secondary 3, and the material to be welded is supplied with the necessary current. When the potential of the source reverses, the conductive discharge device 15 is rendered non-conductive and the other device 17 is thereafter rendered conductive. The current of the opposite polarity now flows through the welding transformer 1.

Since the anode 35 and the cathode 51 of the conductive discharge device are connected respectively to the cathode and the anode of the non-conductive device, the potential impressed across the latter is equal to the potential drop across the former, and is, therefore, relatively small. The ignition potential supplied in the control circuit of the non-conductive device, therefore, has no tendency to produce backfire.

The energizing coil 93 of the timing relay 83 is connected across the primary 9 of the welding transformer in a circuit which extends from the right-hand terminal of the primary 9 through a resistor 95, the coil 93 of the relay, a conductor 97 to the left-hand terminal of the primary. When the transformer 1 is energized, current flows through the coil 93 of the timing relay and the timing lever 99 is raised. The lever moves for an interval of time predetermined by the setting of a cam 101 on which it is supported, and thereafter engages the lower one of a pair of levers 103 and 105 pivotally suspended together from one leg of the armature 107 of the relay. The lower pivotal lever 103 carries the movable contact 79 which is initially engaged with the fixed contact 81 and another movable contact 109 which engages a cooperative fixed contact 111 when the suspended levers are pivoted by the timing lever. The direct connection between the coil 75 in circuit with the grid 77 of the tube 55 and the cathode 59 is now opened and another circuit is completed through the closed contacts 109 and 111 and the taps 67 and 89 of the voltage divider 69. The biasing potential of the voltage divider 69 is thus reapplied to the oscillator tube 55 and it is rendered non-conductive. The application of alternating po-

tential to the ignition electrodes 47—49 is, therefore, interrupted and the discharge device which is last conductive continues to conduct until the end of the half-period, and thereafter the current flow through the welding transformer 1 ceases.

The upper pivotal lever 105 of the timing relay 83 also carries a movable contact 113 which engages a fixed contact 115 when the lever is pivoted by the timing lever 99. Through the latter contacts a circuit is now closed which extends from the upper line conductor 11, through a resistor 117, the contacts 115 and 113 of the timing relay 83, a conductor 119, the energizing coil 93 of the timing relay 83, and the conductor 97 to the lower line conductor 13. The circuit just traced replaces the circuit through the primary 9 of the transformer 1 in providing the necessary current through the coil 93 to maintain the relay 83 energized and the system remains in a condition such that welding current flow cannot be reinitiated until it is reset by the release of the circuit controller 87. The latter is provided with a third contact 121 which closes when the controller is released and short circuits the coil of the timing relay. The system is then reverted to a condition such that another welding operation may take place.

Although we have shown and described certain specific embodiments of our invention, we are fully aware that many modifications thereof are possible. Our invention, therefore, is not to be restricted except insofar as is necessitated by the prior art and by the spirit of the appended claims.

We claim as our invention:

1. In combination, an electric discharge device including a cathode of the pool type and an ignition electrode comprising a conductor covered with a layer of insulating material of the order of several thousandths of an inch in thickness in contact with said cathode and means for applying a potential having a frequency of the order of from several hundred to several hundred thousand cycles per second between said conductor and said cathode to render said device conductive.

2. In combination an electric discharge device including a cathode of the pool type and an ignition electrode comprising a conductor covered with a layer of insulating material of the order of .003 inch in thickness in contact with said cathode and means for applying an alternating potential for a time interval of the order of 100 micro-seconds between said conductor and said cathode to render said device conductive.

3. In combination an electric discharge device including a cathode of the pool type and an ignition electrode comprising a conductor covered with a layer of insulating material in contact with said cathode and means for applying an alternating potential for a time interval of the order of 100 micro-seconds between said conductor and said cathode to render said device conductive.

4. In combination an electric discharge device including a cathode of the pool type and an ignition electrode comprising a cathode covered with a layer of insulating material in contact with said cathode and means for applying an alternating potential having a frequency of the order of from several hundred to several hundred-thousand cycles per second continuously between said conductor and said cathode to render said device conductive.

5. For use in supplying power from a source to

a load the combination comprising a plurality of electric discharge valve means so interposed between said source and said load that when one of said valve means conducts current it substantially absorbs the potential across the other valve means, each said valve means including a cathode of the pool type and an ignition electrode comprising a conductor covered with insulating material in contact with said cathode and means for supplying an alternating potential continuously between the conductors and cathodes of all said valve means.

6. For use in supplying power from a source to a load the combination comprising a plurality of electric discharge valve means so interposed between said source and said load that when one of said valve means conducts current it substantially absorbs the potential across the other valve means, each said valve means including a cathode of the pool type and an ignition electrode comprising a conductor covered with insulating material in contact with said cathode and means for supplying an alternating potential having a frequency of the order of several hundred to several hundred-thousand cycles per second continuously between the conductors and cathodes of all said valve means.

7. For use in supplying power from a source to a load the combination comprising a plurality of electric discharge valve means so interposed between said source and said load that when one of said valve means conducts current it substantially absorbs the potential across the other valve means, each said valve means including a cathode of the pool type and an ignition electrode comprising a conductor covered with insulating material having a thickness of the order of .003 inch in contact with said cathode and means for supplying an alternating current having a frequency of the order of several hundred to several hundred-thousand cycles per second continuously between the conductors and cathodes of all said valve means.

8. For use in supplying power from a source to a load the combination comprising a plurality of electric discharge valve means so interposed between said source and said load that when one of said valve means conducts current it substantially absorbs the potential across the other valve means, each said valve means including a cathode of the pool type and an ignition electrode comprising a conductor covered with enamel having a thickness of the order of .003 inch in thickness in contact with said cathode, and means for supplying an alternating potential having a frequency of the order of several hundred to several hundred-thousand cycles continuously between the conductors and the cathodes of all said valve means.

9. For use in supplying power from a source of alternating current to a load the combination comprising a pair of electric discharge valves interposed between said source and said load to conduct alternate half-cycles from said source to said load, each of said valves including a cathode of the pool type and an ignition electrode comprising a conductor covered with insulating material in contact with said cathode and means for supplying alternating potential continuously between the conductors and the cathodes of both said valves.

10. For use in supplying power from a source of alternating current to a load the combination comprising a pair of electric discharge valves interposed between said source and said load to con-

duct alternate half-cycles from said source to said load, each of said valves including a cathode of the pool type and an ignition electrode comprising a conductor covered with insulating material in contact with said cathode and means for supplying alternating potential having a frequency of the order of several hundred to several hundred-thousand cycles continuously between the conductors and the cathodes of both said valves.

11. For use in supplying power from a source of alternating current to a load the combination comprising a pair of electric discharge valves connected in anti-parallel between said source to said load, each said valves including a cathode of the pool type and an ignition electrode comprising a conductor covered with insulating material in contact with said cathode and means for

supplying alternating potential continuously between the conductors and the cathodes of all said valves.

12. For use in supplying power from a source of alternating current to a load the combination comprising a pair of electric discharge valves connected in anti-parallel between said source to said load, each said valves including a cathode of the pool type and an ignition electrode comprising a conductor covered with insulating material in contact with said cathode and means for supplying alternating potential having a frequency of the order of several hundred to several hundred-thousand cycles continuously between said ignition electrodes and said cathodes of both said valves.
